CURTAIN, CURTAIN STRETCHER, AND
STRETCHER CLAMPFrederick W. Schimmel, Bay City, Mich., and
John M. Straub, Cleveland, Ohio

Application April 12, 1938, Serial No. 201,524

4 Claims. (Cl. 45—24)

This invention relates, as indicated, to a novel curtain, stretcher therefor, and clamp or bracket used in conjunction with such stretcher.

A primary object of the invention is to provide a stretcher for laundered and dry-cleaned curtains which will be effective to stretch the curtain to its original size and dimensions, without in any way distorting the same, and without injury or damage to the curtain, such as has heretofore resulted from the use of curtain stretchers embodying pins and edge clamps.

Another object of the invention is to provide a novel clamp or corner bracket, which can be readily applied to the stretcher for the purpose of rigidly holding the same in adjusted condition; which can be quickly and easily removed from the stretcher; which does not in any way interfere with the stretching operations; which does not come into contact with the curtains or adjacent the corners thereof, and which consists of a minimum number of easily manufactured parts.

A further object of the invention is to provide a novel curtain, which is particularly adapted to be stretched by means of the curtain stretcher of this invention, although it is to be understood that other curtains having certain of the novel features of the present curtain may be stretched by the use of the present stretcher, and that conventional types of curtains may be stretched by means of this stretcher by altering the curtains in a manner to be hereinafter described.

To the accomplishment of the foregoing and related ends, said invention, then, consists of the means hereinafter fully described and particularly pointed out in the claims.

The annexed drawing and the following description set forth in detail certain structure embodying the invention, such disclosed means constituting, however, but one of various structural forms in which the principle of the invention may be used.

In said annexed drawing,

Fig. 1 is a plan view of our improved stretcher, in assembled and clamped condition, with a fragment of a curtain secured thereto;

Fig. 2 is a perspective view of the lower right hand corner of the stretcher of Fig. 1, on an enlarged scale;

Fig. 3 is a perspective view of the reverse side of the elements shown in Fig. 2;

Fig. 4 is a fragmentary cross-sectional view, taken on the line 4—4 of Fig. 2;

Fig. 5 is a fragmentary cross-sectional view, taken on the line 5—5 of Fig. 2; and

Fig. 6 is a fragmentary cross-sectional view, taken on the line 6—6 of Fig. 1.

Referring now to the drawing, the stretcher is seen to comprise top and bottom members 1 and side members 2, the members 1 being preferably made from stainless steel bars of substantially rectangular cross-section, about 8 ft. long, about 1 inch wide and about $\frac{1}{8}$ inch thick, and the members 2 being made of similar stock, and being about 4 feet in length. If desired, these bars 10 may be made of ordinarily cold-rolled steel, which has been cadmium coated to resist corrosion. Each bar is provided with one inch graduations, the graduations being numbered in each direction from the center of each bar, as indicated in Fig. 1, so as to facilitate proper assembly of the bars and stretching of the curtains to their original form and dimension. The bars, it may be noted, are entirely devoid of pins, hooks, edge clamps and the like, which might tend to injure or mark 15 the curtains in any way.

The bars 1 and 2 are adapted to be maintained in assembled relation, with their ends overlapped, as shown in Fig. 1, by means of corner clamps or brackets 3. Each of the clamps 3 is preferably formed from a strip of stainless steel or cadmium-coated steel, about 9 inches long, about 3 inches wide and about $\frac{1}{8}$ inch thick, and comprises a body portion 4, which extends at an angle of about 45° to the bars 1 and 2, end portions 5, which extend at an angle to the portion 4 and transversely of the bars 1 and 2, and rebent flanges 6, which are spaced from the end portions 5 a distance approximately the thickness of the bars 1 and 2. The flange 6 at one end of the clamp, it may be noted, is disposed at the opposite face of the body 4 from that at which the flange 6 at the other end of the clamp is disposed. The portions 5 and flanges 6 of each clamp form channels or passages for the bars 1 and 2, and 20 may be clamped to such bars by means of bolts 7 and wing nuts 8.

The bolts 7 have square shank portions 9, which are adapted to enter square openings 10 in the flanges 6 so as to prevent turning of the bolts 45 when the wing nuts 8 are turned to loosen or tighten the clamps on the bars 1 and 2. The bolts as shown in Fig. 6 extend through portions of the body 4 and flange 6, which are spaced from the bars 1 and 2, so that in securing the bracket 50 to the bars and clamping the same thereto, it is unnecessary to drill holes in the bars. Moreover, the bars are so clamped that no injury can result thereto from the clamp securing devices, i. e., the bolt 7 and nut 8.

The stretcher is particularly adapted for stretching curtains having pockets at the sides as well as at the top and bottom thereof, and each pocket must be open at each end. Such a 5 curtain may be made in a variety of ways, a preferred form of curtain being shown in the drawing, wherein reference numeral 11 designates the front face of the curtain, and 12 the reverse face thereof. The front face is free from hems, all 10 of the hems being exposed at the rear face of the curtain.

The side pockets 13 of the curtain are formed by folding the material at the sides to form a layer 14 which is in contact with the face 12 15 and a layer 15, which overlies the layer 14, the layers 14 and 15 being stitched to the body of the curtain at the edges by means of lines of stitching 16 and 17. A portion 18 of the layer 15 adjacent the bottom is cut away from the 20 layer 14, as at 19 (Fig. 3), and this portion is left unstitched to the curtain at its edges, so as to permit the bottom pocket 20 of the curtain to be formed.

The pocket 20 is formed by folding the material at the bottom of the curtain to form a layer 21 which overlies the face 12 of the curtain, and is secured thereto, as by a line of stitching 22. After the pocket 20 has been thus formed, the portion 18 of the layer 15 is stitched at the sides 30 thereof to the layers 21 and 14 by means of lines of stitching 23 and 24.

The top pocket (not shown) of the curtain is made in a manner similar to the bottom pocket, so that further description thereof is deemed unnecessary.

In stretching the curtain, the top bar 1 is first inserted through the top pocket of the curtain, and the bar then supported at its ends on any suitable supports, the curtain hanging freely 40 from the bar. The bottom bar 1 is then inserted through the bottom pocket 20 of the curtain. The side bars 2 are then inserted through the side pockets 13 of the curtain. The curtain and bars are then adjusted, and the clamps 3 applied to the bars as shown in Fig. 1 to lock them in 45 adjusted position and maintain the curtain in stretched condition pending drying thereof.

Due to the fact that the channels or passages formed by the portions 5 and flanges 6 of the 50 clamps 3 are open at one side, the clamps may be applied to the bars and removed therefrom by a sidewise movement, thus facilitating assembly and disassembly of the stretcher. Moreover, since the body portions 4 of the clamps extend 55 at an angle to the bars 1 and 2, they brace and rigidify the stretcher assembly in a highly desirable manner. Furthermore, since the body portions 4 of the clamps are remote from the points where the bars 1 and 2 overlap, and since

the clamps are secured to the bars at points thereon which are beyond said overlapping areas, the clamps cannot, in any way, interfere with the stretching operation, or injure or deface the curtain.

Conventional types of curtains having hems at the sides as well as the top and bottom thereof may be stretched by means of the present device, if the pockets formed by the ends are opened at the ends, and portions of the seams which 10 would otherwise obstruct the passage of the bars are removed.

Other modes of applying the principle of our invention may be employed instead of the one explained, change being made as regards the 15 structure herein disclosed, provided the means stated by any of the following claims or the equivalent of such stated means be employed.

We therefore particularly point out and distinctly claim as our invention:

1. A clamp for curtain stretchers and the like, comprising a body, flat end portions extending from said body portion at an angle thereto and at right angles to each other, and flat rebent flange portions spaced from said end portions, 25 one of said flange portions being disposed at the opposite face of the body from that at which the other flange is disposed.

2. A clamp for curtain stretchers and the like, said clamp being formed from a single piece of 30 metal and comprising a body portion, flat end portions extending from said body portion at an angle thereto and at right angles to each other, and flat rebent flange portions over-lying said end portions and spaced from the latter.

3. A clamp for curtain stretchers and the like, said clamp being formed from a single piece of metal and comprising a body portion, end portions extending from said body portions and at an angle thereto, flange portions extending from 40 said end portions in planes at right angles to the plane of said body and end portions, one of said flange portions extending from the plane of said body portion in a direction opposite to that of said other flange portion, and rebent portions extending from said flange portions and parallel with said end portions, said rebent portions over-lying said end portions.

4. A clamp for curtain stretchers and the like, said clamp being formed from a single piece of 50 metal and comprising a body portion and clamp portions of U-shaped cross-section extending from the ends of said body portion at an angle to the latter and at right angles to each other, and means interconnecting the flanges of said 55 clamp portions.

FREDERICK W. SCHIMMEL.
